United States Patent Office.

WILLIAM B. INGERSOLL, OF NEW YORK, N. Y.

Letters Patent No. 66,350, dated July 2, 1867; antedated June 27, 1867.

IMPROVED BED-BOTTOM.

The Schedule referred to in these Letters Patent and making part of the same.

Be it known that I, WILLIAM B. INGERSOLL, of the city of New York, and State of New York, have invented a new and improved Bed-Bottom; and I do hereby declare that the following is a full and exact description thereof. And furthermore, I desire that Letters Patent of the United States may be granted to me and my legal representatives for the same.

a a are cross-bars. To these bars is attached a number of pulleys around which a small rope or cord is passed. *r* is the rope; *c* are the pulleys; *h h* are arms to which the cross-bar at the head of the bed is attached, one arm at each end of the cross-bar, the other ends of the arms being attached to the side of the bedstead in such a manner as to allow the cross-bar to move up and down. *f f* are springs placed under each arm, or may be placed under the cross-bar, and may be made of steel, India rubber, or any other suitable material, and of any desired form. *g* is a windlass to which one end of the rope is fastened. At one end of the windlass is a ratchet-wheel and click for the purpose of tightening the cord. By this arrangement the different parts can easily be put together, and in a few moments made to fit any common bedstead. Figure 3 is also a different arrangement, which may be applied to the side of the bedstead or fastened to one of the cross-bars. *p p* are pulleys or rollers. *o* is a ratchet-wheel attached to one pulley, which is corrugated. One end of the rope is passed between the pulleys, and as the pulley with the ratchet is turned the rope is drawn through but cannot slip back, as the click and ratchet prevent the pulleys from turning, and in this way the cord is drawn tight. Having the cross-bar at the head of the bed to move up and down, a true inclined plane is secured, giving to the head of the bed one inch or six inches more or less elevation above the level, just as much or as little as is desired. Also, by this arrangement the cord is made tighter as the weight of the body presses down on it. A bed-bottom so arranged will not sag in the middle. For a full-sized bed fifteen or sixteen pulleys are required, and should be about three inches in diameter, and the spaces between them the same; a little more or less will answer. The pulleys may be made of wood or metal.

What I claim as my invention, and desire to secure by Letters Patent, is—

The combination of the pulleys *c*, around which the cord *r* passes, the cross-bars *a*, to which the pulleys are attached, the movable arms *h*, the windlass *g*, and the springs *f* under the arms or head-piece or cross-bar, all as and for the purpose specified.

WILLIAM B. INGERSOLL.
